UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PNEUMATIC SYSTEM.

Application filed August 19, 1921. Serial No. 493,566.

To all whom it may concern:

Be it known that I, BURTON S. AIKMAN, a citizen of the United States, residing at Milwaukee, in the county of Milwaukee and State of Wisconsin, have invented a certain new and useful Improvement in Pneumatic Systems, of which the following is a full, clear, concise, and exact description, reference being had to the accompanying drawings, forming a part of this specification.

My invention relates to pneumatic systems, and more particularly to the mechanism for controlling the generation and distribution of motive fluid in a system of this character.

While I shall illustrate and describe my invention in connection with a water supply system of the pneumatic displacement and faucet controlled type to which my invention is peculiarly adapted, I do not intend to limit the invention to this particular use.

In systems of this character, air is stored in a reservoir at a pressure considerably higher than the pressure required for operation of the pump, and it is supplied to the pump or other operating device through a pressure reducing valve which holds a substantially constant low pressure upon the pump or other air operated device.

It is sometimes desirable in systems of this character to throw full reservoir pressure upon the pump or other device as, for instance, in supplying water for fire extinguishing purposes.

I provide, according to the present invention, a control valve containing a pressure regulating valve and further means for bypassing the pressure regulating valve, so that by the throw of a lever or other simple movement which is under manual control, the full reservoir pressure may be applied to the pump or other device. By an operation equally simple, the by-pass may be closed, and the function of the regulating valve restored. In this way, I do not disturb the setting or adjustment of the pressure regulating valve in any manner.

In situations where the compressor is manually started as is often the case where a gas engine drives the compressor, it is customary to start the compressor at once when full pressure is desired on the pump, so that

the pressure in the reservoir will not at once be depleted.

In systems where an electric motor or other means suitable for automatic stopping and starting is provided and an automatic controller is used, it would be necessary either to manipulate the automatic controller, or else to wait until the pressure in the reservoir is depleted to minimum to start the compressor.

According to my invention, I provide an automatic controller and cooperating means in the control or regulating valve for automatically starting the compressor when the by-pass about the automatic pressure regulating valve is opened. Thus, no matter what is the pressure in the main reservoir, the compressor will be put into operation at once as soon as full reservoir pressure is thrown upon the pump line. The control valve does not disable the automatic controller for starting and stopping the compressor, so that the attainment of maximum pressure in the tank automatically stops the compressor, even though the regulating valve is by-passed. I accomplish this function by connecting the automatic controller to the main reservoir through the control valve and cause the control valve to make a reduction in pressure in the controller connection when the valve is shifted from one position to another. But the control valve again establishes full connection between the controller and the regulator as soon as a movement is completed so that the regulator can function to cut out the operation of the compressor if the maximum tank pressure is reached.

In pneumatic systems of this type, there is sometimes a demand for air for miscellaneous purposes at a pressure considerably higher than the minimum of the tank. For instance, on a farm or a suburban place where a pneumatic displacement water supply system is employed, it is often desirable to provide means for inflating automobile tires and the like. The pressure that is required is considerably above that at which the usual water supply system operates, and should be relatively high to insure quick and certain filling of the tires. This means that substantially maximum pressure of the reservoir is desirable. In general, it would be

unsatisfactory to tap a connection directly to the reservoir because it would generally be necessary either to blow off the reservoir pressure until the controller cuts in or to wait until a certain amount of pressure is utilized in the normal operation of the system, so that the controller would cut in the compressor and raise the reservoir pressure to maximum.

According to my invention, I provide a connection through the control valve which controls the supplying of pressure to the miscellaneous purposes above described, such that the delivery of air to the filling hose of the supply pipe may be accomplished without disturbing the water system and its automatic pressure regulating valve. At the same time, I provide means for making a reduction in pressure in the connection between the automatic controller and the tank, so that the compressor will be started at once. This is desirable, since the lower portion of the pressure range between maximum and minimum is not sufficient for the service required, and it is necessary to pump up the pressure in the tank. This connection also does not disable the automatic controller, for its function of cutting out the action of the compressor as soon as the pressure in the tank attains the maximum.

The control mechanism shown and described herein makes provision for these three conditions or demands above enumerated; first, normal or automatic pressure regulating condition; second, fire condition; and third tire filling condition.

I provide a simple, unitary valve structure for controlling the system to satisfy the above conditions.

In order to acquaint those skilled in the art with the preferred embodiment of my invention, I shall now describe the embodiment illustrated in the accompanying drawings, in which:

Figure 1 is a diagrammatic illustration showing a system embodying my invention;

Figure 2 is a transverse vertical section taken through the pressure regulating valve;

Figure 3 is a front elevation of the valve, indicating the different position of the handle for securing the desired operations;

Figure 4 is a vertical section of the controller;

Figure 5 is a rear elevation of the manual valve casing viewed on line 5-5 of Figure 2 looking in the direction of the arrow;

Figure 6 is a section taken on line 6-6 of Figure 5, looking in the direction of the arrows;

Figure 7 is a section taken on line 7-7 of Fig. 8 through that part of the valve member comprising the reservoir and pump inlet;

Figure 8 is a section of the same portion of the valve taken on the line 8-8 of Fig. 7;

Figure 9 is a section of the valve member taken on line 9-9 of Figure 7;

Figure 10 is a section taken on line 10-10 of Figure 2, looking in the direction of the arrows, illustrating the valve set at normal condition;

Figure 11 is a similar view, illustrating the valve set at fire condition; and

Figure 12 is a likewise similar view with the valve set at tire condition.

As shown in Figure 1, a single cylinder pump 1 of any preferred construction is submerged in the water 2 of the well 3. This pump has the usual water inlet and outlet valves and compressed air admission and exhaust valves (not shown). The pump has a water discharge connection 4 connected to the water discharge pipe 5 through a suitable check valve 6. The water discharge pipe leads to the combined steady flow chamber and air injector 7, and from thence leads to the outlets, in this case shown as the faucets 8 and fire hose 50. The combined steady flow chamber and injector 7 are shown and claimed in my co-pending application Serial No. 456,842, filed March 30, 1921 to which reference may be had for further description. The pump 1 is supplied with compressed air from a reservoir 10 through a pressure reducing valve 11 and pipe 12, for discharging the water into the distributing system. The pump is provided with an exhaust pipe 13.

The reservoir 10 may be re-charged by means of a compressor 14, which may be driven by any suitable power device, in this case the motor 15. An automatic controller and cut-off valve 16 is connected between the reservoir 10 and compressor 14. This automatic controller has a diaphragm chamber 19 connected to the reservoir 10 through pipe 20 and valve 11. The diaphragm 23 is normally subject to the pressure in the reservoir so as to control the starting and stopping of the motor 15 and compressor 14 automatically. This is accomplished by controlling the motor circuit by the pressure controlled switch 17, which may be of any preferred character. The particular controller switch which I have illustrated is known in the art as a type "CD-3" governor.

The automatic controller and shut-off valve 16 is disclosed and claimed in my co-pending application, Serial No. 456,843, and filed March 30, 1921, but, I shall describe this device 16 so as to convey a general understanding of its operation and the particular relation it has to the present arrangement.

The movable switch contact 18 is controlled by the diaphragm 23 which is subjected on its lower side to the pressure in the chamber 19, this chamber being in communication with the reservoir 10 through pipe 20, control valve 11, and pipe 21. A

movable spring pressed piston 24 rests upon the top of the diaphragm, this piston being held against the air pressure by a spring 22. The piston 23 is guided by a series of pins 25, lying in holes in plate 26 above the diaphragm 23. The pins 25 engage the lower side of a collar 27, which is pressed downwardly by the spring 22 to oppose the pressure of the diaphragm. The collar 27 has a groove which embraces a transverse rod 28 connected to the sides of the levers 29, which levers are pinned upon a common cross shaft or pivot 30 at the rear of the controller or governor. The levers 29 are connected together by a snap spring (not shown) to form a toggle mechanism with short arms 31 at the outer end, the arms 31 carrying the movable contact 18. This contact is connected to one side of the circuit. The other side of the circuit is connected to the stationary contact 32. The toggle action of levers 29 and arms 31 provide a quick movement of contact 18 in engaging and breaking with contact 32.

The compressor 14 and tank 10 are connected through pipes 33 and 34, which are separated by a valve casing 35 which serves as a suitable support for the controller 17. The valve casing contains a passageway therethrough, which is obstructed by the walls 36 and 37, the wall 36 having a passageway 30 therethrough, normally obstructed by a ball check valve 38, this check valve 38 being guided by a tubular extension 39 of the pop valve 40. The wall 37 contains a passageway 41, which passageway is controlled by a cut-off valve 42. This valve 42 has a stem 43, which is fluted to permit the air to pass the same. The stem 43 passes through a cover plate 44, upon which rests a spring 45 tending to raise the valve 42 against a slot 46 which is formed in the cover plate 44. A button 47 of insulation material lies above the stem and engages the under side of the contact 18, so that when the contact is lowered, the button will be pressed down and will engage the stem to open the valve 42 away from its upper seat 46 and close it against the lower seat. The air confined in pipe 33 will rapidly escape, thereby unloading the compressor.

The control valve 11, as illustrated in Figure 1, has four connections leading thereto, namely, the reservoir pipe 21, the controller pipe 20, the air pipe 12 to the pump and a connection 48 leading to the tire hose 49.

As shown in Figures 2, 3, 7 and 8, I provide a valve casing 51 with an inlet and an outlet on opposite sides, the valve mechanism being set in a vertical bore 52 in said casing. This vertical bore 52 is directly connected to the air inlet 53, which, in turn, is connected with the air reservoir 10 through the pipe 21. The air inlet, which goes to the

water pump, is indicated at 54. It is directly connected with the axial bore 55 which is separated from the axial valve chamber 52 by means of the partition 56, in which an axial opening 57 is provided. 70

A valve 58 is disposed for vertical movement in the valve chamber 52, and it is provided with a yielding face 59, which is adapted to cooperate with the valve seat 60 surrounding the opening 57. The top of the valve chamber 52 is closed by a screw plug 61 between which and the valve 58 a spring 62 is disposed. Threaded into the valve member 58 is a stem 63 which extends downwardly through the opening 57 for engagement with the diaphragm stem 76'. 75

The underside of the casing 51 is flared out to form the upper portion of a diaphragm chamber 64 defined in part by a flexible diaphragm 65 clamped to the flange 66 of the casing 51 by means of the lower cover plate 67 and the screws 68, 68. Threaded into the lower cover plate 67 is a downwardly extending post 69 at the bottom of which a circular plate 74 is supported upon a nut 70, the latter being held in place by means of a lock nut 71. A collar 72 loosely surrounds the post 69 and a coiled spring 73 is disposed between the plate 74 and the collar 72. 90

Between the diaphragm 65 and the lower cover plate 67, a diaphragm plate 75 is disposed. This plate, by means of pins 76 extending through the lower cover plate 67, is mechanically connected with the collar 67, so that the influence of the spring 73 upon the collar 72 may be transmitted to the diaphragm plate 75 and in turn to the diaphragm 65. 100

A stem 76' is mounted loosely in the axial bore 55, this stem being so arranged that, at the top, it may engage with the valve stem 63, which has hereinbefore been referred to. The stem 76' is preferably formed integral at its lower end with the diaphragm plate 75, passing through the diaphragm 65 in a gas tight joint, being threaded at that point and for a short distance thereabove to accommodate the nut 77 which tightly holds a washer 78 against the diaphragm. 110

The description thus far given of the reducer valve is of that portion of the entire device 11 relating to the reduction of the air pressure to the pump 1. 120

The valve casing 51 is provided with a flat face having a circular flange 80 which is disposed preferably parallel to the axial passageway 52-57. Between the flange 80 and air inlet 53 and air outlet 54, two chambers 81 and 82 are provided, the chamber 81 communicating with the air inlet and with a port 83 in the flange 80, and the chamber 82 communicating with the air outlet 54 and a port 84 also in the flange 80. 130

A rotary valve casing 85 is mounted on the flange 80 of the valve casing 51 by means of the flange 86 and bolts 87, with a gasket 89 interposed between the flanges. The 5 valve casing 85 is provided with the tapered rotary valve bore 88 which is adapted to receive the rotary valve 90, compression spring 91 holds the valve 90 to seat in the bore 88. The outer end of the valve 90 is reduced to 10 receive a handle 92, upon which is formed a pointer 93 to indicate externally the angular position of the valve 90 within the casing 85. When the handle 92 is moved to the right, say on the dotted line indicated by 15 letter F, the rotary valve 90 by-passes air at reservoir pressure to the pipe 12. When the handle 92 is moved to left, to the dotted line indicated by letter T, the rotary valve 90 is set to supply air at reservoir pressure to the tire hose 49.

Referring now to Figure 6, it will be seen that the valve casing 85 is provided with passageways 94 and 95, which have connection with cross passageways 96 and 97 respectively, formed by drilling radially into the body 85 and then plugging the outer ends by the plugs 98. The port 83 in the valve casing 51 registers with the passage 94, while the port 84 also in the valve casing 51 registers with the passage 95. Hence, the pressure in the passage 94 will be equal to that of the reservoir. The rotary valve casing 85 is also provided with a threaded pipe socket 100 communicating with the 30 axial tapered bore 88 through the port 101. Pipe 48 leading to the tire hose 49 connects with the socket 100 for supplying air from the reservoir 10 for tire filling purposes. Opposite to this socket 100 is a socket 102 35 to which is connected the pipe 20 leading to the automatic controller 16. This socket 102 communicates with the inner end of the axial bore 88 through a port 103. The rotary valve 90 has a central bore running out 40 to the ports 105 and 106 which extend laterally to the surface of the plug or valve 90. A peripheral passageway 107 lying between the ports 105 and 106 communicates with the central bore 104 by means of the restricted radial passageway 108.

The operation of the device is as follows:

Assume that the system is in operation and the parts are in the position shown in Fig. 1. The pressure in the pump line 12 will be maintained at a certain value, sufficient to drive the water through the pipe 5 to the outlets 8. If the faucet 8 or the hose 50 is opened water flows therefrom due to the automatic operation of the pump 55 1. When the pressure in the reservoir 10 falls below minimum, the automatic controller 16 is actuated to close the motor circuit. The motor 15 then drives the compressor to restore the pressure to maximum before the circuit is broken. The pressure supplied

to the pump is automatically maintained at a given value by the reducing valve 11, which is set to give suitable pressure at the faucets when the pump is delivering its 70 rated capacity.

The compressed air passes from the reservoir 10 through the pipe 21, through the air inlet 53 and flows to the valve chamber 52 and also to the chamber 81. It will be seen from Figure 2 that this compressed air will act on the valve member 58 with the tendency to hold the same upon its seat 60. The spring 73 is adjusted by the nuts 70 and 71 and plate 74 to have a sufficient strength to balance the spring 62 and equalize the pressure of air at the desired reduced pressure acting upon the top of the diaphragm 65. If the air on the diaphragm 65 is permitted to expand as for instance when the pump 1 is operated, the spring 73 85 overpowers the diaphragm 65 and thrusts the valve 58 off of its seat. Compressed air will then flow from the valve chamber 52 through the passage 57 and into the chamber 55, from whence it moves on into the outlet connection 54. The pressure is thus maintained at a substantially constant valve. 90

The rotary valve 90 now lies in the position shown in Figure 10. The compressed air flows from the chamber 81 through the port 83 into the passageway 94 of the valve casing 85. From the cross passageway 96 the air flows along the peripheral passageway 107 through the radial port 108 into the axial passageway 104 and from there to the controller connection 102 by means of the passageway 103. Thus, the controller 16 is subjected to the pressure existing in the reservoir 10, and the lowering of the pressure to a predetermined minimum will operate to close the motor circuit and to start the compressor 14. When the pressure in the chamber 19 (Figure 4) drops to the minimum it permits the spring 22 to drop the diaphragm piston 24. This causes 100 actuation of the toggle mechanism which includes the levers 29 and 31, resulting in raising the movable contact 18 to engage the stationary contact 32 whereby the circuit is closed. By the same action the cut-off and unloading valve is shifted to its upper position as soon as maximum pressure is attained in the chamber 19, the reverse action 110 of the controller elements takes place to open the circuit and to shift the cut-off and unloading valve. 115

When it is desired to use the fire hose, the valve handle is thrown to the right bringing the plug valve 90 into the position shown in Fig. 11. This motion also 125 produces a reduction in pressure in the controller 16 causing it to start the compressor at once. The handle 92 is moved to the right to the position indicated by the dotted line F shown in Figure 3. By such setting, 130

the pressure regulating valve is by-passed. As the rotary valve 90 is rotated in the direction of the arrow shown in Figure 11, the port 106 will come in communication with the passageway 97 before the port 105 is in communication with the passage 96. As the passageway 97 communicates with pipe 12 leading to the pump 1, the pressure in the controller connection drops due to the expansion of the air in pipe 20 and chamber 65 into pipe 12 and pump 1. Thus, there is caused what may be termed a flash-off of pressure in the controller line 20 to close the motor circuit. This action of the controller to start the compressor is the same as explained hereinbefore.

It will be noted that the reservoir communicates with the controller during this initial movement only through the restricted port 108 so that the pressure in the controller line flashes over into the relatively low pressure line 12 before reservoir pressure can be restored. The automatic controller is affected thus only momentarily, but it will not cut out again until maximum pressure is reached.

As the valve 90 comes to rest, as shown in Figure 11, the compressed air entering the inlet 53 flows into the chamber 81, through the port 83 and into the passageway 94 where it passes through valve ports 105, 106 into the passageways 97 and 95. From the passageway 95, the compressed air flows through the port 84, the chamber 82 and through the outlet 54 and pipe 12 leading to the pump. Thus, a direct passageway independent of the pressure regulating valve is established from reservoir 10 to pump 1 without any disturbance of the adjustment of the pressure reducing valve. While this condition exists, the compressor continues to operate until the pressure has been raised to maximum, whereupon the controller is influenced to cut out the motor circuit. At no position of the control valve, even in intermediate positions is there any danger of the reservoir being blown up since the flash off of pressure in the controller is only temporary and pressure of the reservoir is promptly restored upon the controller. The controller will also cut in said circuit again should the pressure drop to minimum after once having reached maximum.

When the hose 50 is no longer in use, the handle 92 is switched back to normal position. It may be shifted over to tire filling position at one movement if desired.

Assuming that the handle 92 is thrown to the left, to the position indicated by line T, the rotary valve 90 assumes the position shown in Figure 12. In moving to such position, port 106 is closed off and port 105 starts to register with the port 101 connecting with the tire hose 49 through the outlet 100 and pipe 48. Compressed air will flow at once from controller pipe 20 into the empty tire hose momentarily expanding and dropping in pressure to operate the controller to start the compressor. The flow of air thereafter is from the reservoir passageway 96 through the arcuate passageway 107 and port 108 to the port 101. In order to permit said reduction in pressure whereby the controller 16 is influenced to start the compressor 14, the port 101 has been made larger than the passageway 107 and port 108, with the result that the pressure in the controller passageway 104 will be flashed-off while the inflow of air is restricted by port 108. As soon as the final position of the valve is reached, the controller will be freely in communication with the reservoir and will act upon the attainment of maximum to stop the compressor. The pressure reducing valve is meanwhile permitted to function without disturbance in reducing the pressure supplied to the pump 1.

I now wish to call attention to certain important aspects of the invention and permissible variations in embodiment of the same. While I have illustrated the invention in connection with a pneumatic water supply system, it is to be understood that instead of the pump 1, another device or devices driven by compressed air may be substituted without affecting the broad aspect of the invention. In a similar manner, a different device or connection for distributing or using compressed air at reservoir pressure may be substituted for the tire hose 49 without influencing the broad aspect of the invention. It is also possible under the broad aspect of the invention to separate the two functions of the controller valve 11, namely, the pressure reducing function and the by-pass and distributing function into either two or three separate valves without departing from the broad spirit of the invention, although I consider that the combination of these three functions into a single unitary structure provides an improved and highly advantageous device in the art.

It is also permissible within the spirit of my invention to secure the proper connections for the purpose which I have above disclosed by a valve differing from the particular rotary valve 90, which I have shown. That is to say, I am aware that a slide valve or piston valve or poppet valve or any other suitable form of valve may be employed instead of the plug valve, which I have shown. However, I consider that the valve which I have shown is simple and reliable, and is of a preferred type. The control valve may be provided with a remote control and pneumatic operating mechanism without departing from the broad spirit of the invention.

The automatic controller 16 which I have shown is adapted for controlling the elec-

tric motor 15. However, the specific form of this controller is not of the essence of the present invention and other means than an electric circuit may be controlled to secure starting of the means which drives the compressor, or other means for recharging the reservoir 10.

I claim:

10. In combination, a compressor, a reservoir, an automatic controller for the compressor connected to the reservoir, and a control valve in communication with said connection for making a reduction in pressure in said connection to start the compressor said reduction being temporary only.
20. In combination, a reservoir, means for recharging the reservoir, a discharge pipe for the reservoir, an automatic controller for said means connected to said reservoir, and a manually operable control valve in communication with said connection for making a temporary reduction in pressure upon said controller independently of the pressure in said reservoir said valve connecting the controller to the discharge pipe.
30. In combination, a compressor, a reservoir, an automatic controller connected to said reservoir, a device driven by compressed air, a valve for applying pressure from the reservoir to said device, said valve having means for making a reduction of pressure on said controller independently of the pressure in the reservoir to cause the controller to start the compressor said valve providing a relatively free connection between the controller and said driven device, and a relatively restricting connection between said reservoir and said connection.
40. In combination, a reservoir, a compressor, an automatic controller for the compressor connected to the reservoir, a pipe for distributing compressed air from the reservoir, a pressure reducing valve in said pipe dividing the pipe into a high pressure portion and a low pressure portion and a valve for connecting said pipe to said reservoir independently of said reducing valve, said valve having means to influence the controller to start the compressor when the valve is opened, said means comprising a connection between the controller and said low pressure portion of the pipe.
50. In combination, a reservoir, a compressor, an automatic controller governing starting and stopping of the compressor, a pneumatic device operating at a pressure lower than reservoir pressure, a reducing valve between the reservoir and said device, and a manual control valve for supplying compressed air to the device at reservoir pressure, and means for influencing the controller to start the compressor when said control valve is actuated.
60. In a pneumatic system, a reservoir for motive fluid adapted to be maintained at

relatively high pressure, automatic means for recharging the reservoir, a pneumatic device adapted to be operated normally at a relatively low pressure, a pressure reducing valve for supplying motive fluid normally at low pressure to said device, and manually controllable means for supplying motive fluid at reservoir pressure to the device, and for conjointly influencing said automatic means to recharge said reservoir.

70. In combination, a reservoir, a compressor, an automatic controller for the compressor connected to the reservoir, a pipe for distributing compressed air from the reservoir, and a valve for connecting said pipe to said reservoir, said valve having means for causing a reduction of pressure on the controller independently of the pressure in the reservoir to start the compressor when the valve is opened.

80. In combination, a reservoir, a compressor, an automatic controller for the compressor, a pipe for distributing compressed air from the reservoir, a control valve for connecting the reservoir to said pipe, a connection between the reservoir and the controller running through said valve, said valve having a restricted port adapted to be interposed between the reservoir and the controller during the movement of the valve to a position to connect the reservoir and the pipe.

90. In combination, a reservoir, a compressor, an automatic controller for the compressor, a pipe for distributing compressed air from the reservoir, a control valve for connecting the reservoir to said pipe, a connection between the reservoir and the controller running through said valve, said valve having means to influence the controller to start the compressor when the valve is opened, said means comprising a connection between the controller and said low pressure portion of the pipe.

100. In combination, a reservoir, a compressor, an automatic controller for the compressor, a pipe for distributing compressed air from the reservoir, a control valve for connecting the reservoir to said pipe, a connection between the reservoir and the controller running through said valve, said valve having means to discharge the compressed air in the controller connection into the pipe before establishing full connection between the reservoir and the pipe.

110. In combination, a reservoir, a compressor, a controller, a pipe, a valve having three branch connections one leading to the reservoir, a second leading to the controller and a third leading to a distributing pipe and having means to establish a restricted connection between the first and second branch connections, and then an unrestricted connection between the second and third branch connections.

12. In combination, a reservoir, a compressor, a controller, a pneumatic pump, a pressure reducer, a connection from the reducer to the pump, a connection from the reservoir to the reducer, an air distributing pipe, a control valve for connecting the reservoir directly to either the pump or the pipe, and a connection from the controller leading to the reservoir through the valve, said valve having means for temporarily reducing the pressure in the controller connection when said valve is actuated to establish either of said latter connections.
13. A valve comprising a main casing having a diaphragm chamber, an inlet connection, an outlet connection and a valve seat, a diaphragm for the chamber, a pressure reducing valve for the valve seat actuated by the diaphragm, an auxiliary casing having a valve seat, a controller connection and an air distributing connection, said latter connection having a distributing port in said seat, a passageway leading to the inlet connection and providing an inlet port on said seat, a valve cooperating with said valve seat, said valve having a controller passageway in constant communication with the controller connection, a restricted port in the valve and an unrestricted port in the valve, both communicating with said controller passageway, said valve being organized to register the restricted passageway with the inlet port when the unrestricted port is first brought into register with the distributing port.
14. A valve comprising a main casing having a diaphragm chamber, an inlet connection, an outlet connection, and a valve seat, a diaphragm for the chamber, a pressure reducing valve for the valve seat actuated by the diaphragm, an auxiliary casing secured to the main casing, said auxiliary casing having a valve seat, a controller connection and an air distributing connection, said latter connection having a distributing port in said valve seat, a passageway leading to the inlet connection provided with an inlet port on said valve seat, a passageway leading to the outlet connection and providing an outlet port on said valve seat, a valve cooperating with said valve seat, said valve having a controller passageway in constant communication with the controller connection, a restricted port in the valve and an unrestricted port in the valve, both communicating with said controller passageway, said valve being organized to register the restricted passageway with the inlet port when the unrestricted port is first brought into register with either the distributing port or the outlet port.
15. In combination, a main valve casing having a diaphragm and a reducer valve and having inlet and outlet connections to and from said valve, an auxiliary casing mounted on the main casing, said auxiliary casing having a bore providing a valve seat for a tapered rotary valve, a passageway leading from an inlet port on said valve seat to the inlet connection in the main casing, a passageway leading from an outlet port on said valve seat to the outlet port in the main casing, and a rotary valve cooperating with said seat for establishing communication between said inlet and said outlet ports for by-passing the pressure reducing valve.
16. In combination with a pumping system comprising a pump having a source of motive fluid for operating the same, a control member comprising an adjustable pressure reducing valve in the motive fluid line, and means independent of the adjustment of said valve for by-passing the motive fluid around said valve to feed motive fluid at higher pressure to the pump.
17. In combination, with a low pressure compressed air system comprising a pump having a source of compressed air for operating the same, a high pressure pipe connected to said source, a control valve comprising a pressure reducing valve connected to said pipe, a high pressure distributing pipe for compressed air, said control valve having manually controlled means for supplying air at high pressure to said distributing pipe while reducing the motive fluid to said pump.
18. In combination, with a low pressure compressed air system comprising a pump having a source of compressed air for operating the same, a high pressure pipe connected to said source, a control valve comprising a pressure reducing valve connected to said pipe, a high pressure distributing pipe for compressed air, said control valve having manually controlled means for supplying air at high pressure to said distributing pipe while reducing the motive fluid to said pump, and ports controlled by said control valve for by-passing the pressure reducing valve.
19. In combination with a pumping system comprising a pump having a source of motive fluid for operating the same, a high pressure outlet for motive fluid independent of said pump, a control valve comprising a pressure reducing valve for reducing the pressure of the motive fluid supplied to said pump, and having manually controllable means for by-passing said pressure reducing valve to permit motive fluid to flow at a higher pressure to said pump, said means controlling a connection for diverting motive fluid to said independent outlet.
20. In combination, a pump, a reservoir, and a compressor therefor, a controller for the compressor, a valve in the motive fluid line, said valve adapted to reduce the pressure to said pump, and means for by-pass-

- ing said valve to allow motive fluid at high pressure to flow to said pump, said means affecting said controller to start the compressor whereby the reservoir will be replenished.
21. In combination, a pneumatic system, a compressor therefor, a controller affected by the reduction of pressure of the motive fluid in the system to start said compressor, a pressure reducing valve in the system for providing a reduced pressure to a portion of said system and a control valve, said control valve having means for by-passing said reducing valve and for reducing the pressure on said controller to cause starting of the compressor.
22. In combination, a pump having a source of motive fluid and a compressor therefor, a controller affected by a drop in pressure of the motive fluid to start said compressor, a reducing valve for providing a reduced pressure to said pump, a control valve in operative relation with said reducing valve, said controller having communication with said reducing valve through said control valve, said control valve having a position for by-passing the reducing valve, the movement of said valve to said position causing a reduction of the pressure in the controller line.
23. In combination, a pump having a source of motive fluid and a compressor therefor, a controller affected by a drop in pressure of the motive fluid to start said compressor, a reducing valve for providing a reduced pressure to said pump, a control valve having a pair of passages, corresponding ports on each side of said reducing valve for registering with said passages, said control valve having passages adapted to register with one of said first passages in advance of the others to cause a reduction of the pressure in the controller before said reducing valve is by-passed.
24. In combination, a pump having a source of motive fluid and a compressor therefor, a controller in the motive fluid line, a reducing valve also in the motive fluid line for providing reduced pressure to said pump, a control valve connected with said reducing valve, a passage in said control valve subject to pressure on the compressor side of said reducing valve, said controller having communication with said passage, a second passage in said control valve having communication with the pump side of said reducing valve, movement of said control valve placing said passages in communication and causing reduction of the pressure in the controller line to start the compressor.
25. In combination, a pump, a reservoir and a compressor therefor, a controller connected to the reservoir, a reducing valve for providing reduced pressure to said pump, an outlet for compressed air at reservoir pressure, means associated with said reducing valve for diverting a certain amount of the motive fluid to said outlet, said means operating to cause starting of said compressor independently of the pressure in the reservoir.
26. In combination, a pump having a source of motive fluid and a compressor therefor, a controller in the motive fluid line, a reducing valve for providing reduced pressure to said pump, a valve having a passage subject to the pressure on the compressor side of said reducing valve, an air outlet adapted to have communication with said passage by movement of said valve, the initial movement of said valve causing operation of the controller to start said compressor.
27. In combination, a reservoir and a compressor therefor, a valve for transmitting motive fluid at reduced pressure, a second valve for providing a flow of motive fluid at full pressure, and means for initiating operation of the compressor independently of the pressure in the reservoir upon operation of said second valve.
28. In combination, a compressor, a reservoir, an automatic pressure controlled device normally directly connected through the reservoir and governed by the reservoir pressure for stopping and starting the compressor, and a manually operable valve for changing the connection of said controller and for making a temporary reduction in pressure upon said device to start the compressor.
29. In combination, a compressor, a reservoir, an automatic pressure regulated governor under control of the reservoir pressure for stopping and starting the compressor, a connection from said governor to said tank, a distributing pipe for distributing air from the compressor, and a valve for exhausting the air in said governor connection into said distributing pipe to cause a reduction upon the governor for starting the compressor.
30. In combination, a compressor, a reservoir, an automatic pressure controlled governor for stopping and starting the compressor at definite predetermined pressures, said governor having a snap actuating means for starting the compressor at minimum pressure which is considerably less than the stopping pressure, and a manually operated valve for causing said governor to start the compressor independently of the pressure in the reservoir, said governor when so actuated stopping the compressor automatically upon the attainment of the predetermined maximum pressure in said reservoir.
- In witness whereof, I hereunto subscribe my name this 16th day of Aug., 1921.

BURTON S. AIKMAN.
